UNITED STATES PATENT OFFICE

2,413,078

FILING APPARATUS

Richard P. Scholfield, New York, N. Y., assignor to
 Scholfield Service, Inc., New York, N. Y., a corporation of New York

Application May 12, 1944, Serial No. 535,347

6 Claims. (Cl. 129—16)

1

The present invention relates to filing apparatus and, more particularly, to apparatus of the type in which a plurality of filing cards are mounted upon a rotatable drum or support, for ready access for inspection and posting by an operator. Apparatus of this class is exemplified by the prior patents to Scholfield et al., Nos. 2,046,655; 2,205,932; and 2,231,029.

It is an object of the present invention to provide a rotary file which is adapted to be positioned upon a desk, table or other article of office equipment, so as to be conveniently accessible to an operator for quickly getting desired information and so that data may be readily posted or entered upon appropriate cards.

A further object of the invention is to provide an improved apparatus of this type, in which the cards are so arranged that they naturally tend to separate from one another, or spread apart slightly, and, by their own weight, will stay in a separated position when once opened up at a particular place by an operator, for inspection and posting.

A further object of the invention is to provide increased card capacity for a file of given size. Another object is to provide, in a compact rotary file containing a large number of cards, improved means for mounting the cards, which materially facilitates manipulation of the file.

Another object is to provide means for hingedly mounting the cards on the periphery of a drum in such manner that the cards are tipped rearwardly away from the position of the operator, so that they may be inspected more readily than heretofore and so that entries may be posted with greater ease. Another advantage flowing from this arrangement is that the cards normally tend to swing apart and may be quickly and easily separated by the operator, whereupon they will maintain that relation.

Other and further objects and advantages will be apparent to persons skilled in the art from a consideration of the following description of the specific embodiment shown for purposes of illustration in the accompanying drawing and described below.

Rotary files of the type shown in the above patents, and manufactured and sold extensively by applicant's assignee for a number of years, have been of two general types, namely, filing drums mounted for rotation on a horizontal or slightly inclined axis and drums mounted for rotation on a vertical axis. In both types, the rim of the drum has been cylindrical and the cards have been secured at their inner edges on lines parallel to the axis of the drum.

In accordance with the present invention, a radical departure from prior practices has been made, since the rim or periphery of the filing drum is disposed upon an upwardly and in-

wardly inclined surface, such as a frusto-conical surface or a truncated pyramidal surface, the drum being mounted for rotation about its own axis, arranged substantially vertically. This novel structure results in numerous unexpected advantages and in a new mode of operation, as explained below.

In the accompanying drawing:

Figure 1 is a perspective view of the improved apparatus with a plurality of cards mounted thereon;

Figure 2 is a fragmentary vertical sectional view of the drum, showing a card mounted thereon, and

Figure 3 is a plan view of a preferred form of card, with a central section broken away.

The drum 10 is preferably mounted for rotation about a central post 11 extending upwardly from a suitable base 12. The drum 10 may be made of any suitable material, such as molded plastic, cast metal, wood turned on a lathe, or sheet metal, stamped or spun to the desired shape. Bearings 13, 14, as shown in Figure 2 may be employed, or any other type of ball or roller bearings may be substituted. A collar 15, fast on the post 11 constitutes a thrust bearing and supports the weight of the drum and the cards, while a cap 16 on the upper end of the post overlies the bearing 13 and the central portion of the drum.

The rim, circumference or periphery 20 of the drum is preferably disposed upon a frusto-conical surface which is inclined in the neighborhood of 18° to 23° from the vertical as indicated by angle α . Of course, the invention is not restricted to any specific range of inclination of the surface, but the degrees indicated are preferred. Moreover, any other type of upwardly and inwardly tapering surface or surfaces may be employed, such as are provided by a many-sided, truncated pyramid, for instance.

The cards 22 are retained upon the surface of the drum by a pair of circumferentially extending, parallel card retaining rails 23, 24, which may be formed integrally with the drum or separately and secured thereto by any appropriate means. The rails, in cross section, project perpendicularly from the surface of the drum and each comprises a web 25 and a head 26 having arcuate margins struck about spaced centers, as explained in my prior Patent No. 2,231,029. If desired a rail shape of the type shown in Patent No. 2,368,162 dated January 30, 1945, may be employed, with correspondingly shaped slots in the cards. Preferably, the outer end face of the rail head is struck on a relatively flat arc having a rather long radius, while the side faces are disposed on arcs of considerably less radius.

The inner margins 28 of the cards 22 are provided with keyhole shaped slots 29, 30, spaced

apart a distance equal to the spacing of the rails. The slots correspond generally in cross sectional shape to the shape of the rails, and include throats 31 adapted to embrace the webs 25 and enlargements 32 adapted to embrace the rail heads. The slots are slightly larger than the rails, so as to permit the cards to hinge or swing freely about their inner edges, but make line contact with the rails, as explained in the above-mentioned patents.

The cards may be applied to the drum by flexing the margins of the slots opposite the throats 31 and may be deliberately removed in a similar manner, but, because of the structure illustrated, they will not become detached accidentally.

As a result of the angular disposition of the inner edges of the cards, that is, the upward and inward inclination thereof, the weight of each card tends to swing it laterally, from the position shown in Figure 2. This tipping of the cards gives them a somewhat unbalanced characteristic, but when the cards are packed relatively tightly around one portion of the circumference of the drum, they stand substantially radially. When the operator separates the cards at one point, however, their unbalanced condition causes them to spread apart under their own weight and to remain in that relation until manually shifted to a different position. This characteristic of the new arrangement is of material advantage, since an operator need use only one hand in separating the cards and in posting entries thereon or otherwise manipulating the device. There is no danger that the cards will move together and the operator's place be lost.

In view of the fact that the circumference of the drum at its upper end is less than at its lower end, it will be apparent that the cards mounted thereon will be more closely packed at their upper edges than at their lower ones. This results in a spreading or fanning out of the cards and is of material advantage, since each card, at its lower portion is normally spaced a slight distance from its neighbor, thereby facilitating separation of the cards and rapid inspection of data thereon.

In some cases it is desirable to interpose between the central post 11 and the drum, a one-way clutch or brake device, to restrain rotation of the drum in one direction, so that substantial force in that direction may be applied to the drum as when posting entries on cards mounted thereon. Any of the one-way brakes of the types shown in the above-identified Patent No. 2,046,655 may be employed, in a manner which will be entirely clear to one skilled in the art, from a consideration of the patent and the present specification. Alternatively, a one-way clutch and brake device of the type shown in the application of Scholfield and Kelly, Serial No. 499,966 filed August 25, 1943, may be used and, if desired, a handle mechanism of the type shown in that application may be associated with the vertically mounted drum of the present application.

In the drawing forming a part of this specification, only a single drum is shown mounted upon the central post 11, but it must be understood that any number of drums may be mounted, one above the other, co-axially on a common shaft or post, with suitable collars, similar to that shown at 15 and referred to above, or equivalent devices, to maintain the several drums in properly spaced relation. Moreover, the one-way brake and clutch devices and the handle mech-

anism referred to immediately above may be associated with some or all of these co-axially mounted drums.

It is thought that the operation of the apparatus of the present invention and all of the advantages resulting therefrom will be clear from the foregoing description. It should be understood that the invention is not limited to the details of construction shown in the accompanying drawing and described above, but that all modifications coming within the scope of the appended claims and their equivalents are included.

I claim:

1. A filing apparatus comprising a substantially vertically disposed drum supported for rotation about its axis and having a circumferentially unbroken continuous, upwardly and inwardly tapering periphery, circumferentially continuous card retaining means associated with the periphery of the drum, and a plurality of cards retained thereby adjacent their inner edges for lateral swinging movement with respect thereto.

2. A filing apparatus comprising a vertically disposed frusto-conical drum supported for rotation about its axis, and means for retaining a plurality of slotted cards upon its periphery for swinging movement with respect thereto, said means comprising a continuous, circumferentially extending card retaining rail adapted to be received in the slots in the cards.

3. A filing apparatus comprising a vertically disposed frusto-conical drum supported for rotation about its axis, and means for retaining a plurality of slotted cards upon its periphery for swinging movement with respect thereto, said means comprising a pair of spaced, parallel, circumferentially extending card retaining rails adapted to enter spaced slots in the cards.

4. A filing apparatus comprising a vertically disposed frusto-conical drum supported for rotation about its axis, and means for retaining a plurality of slotted cards upon its periphery for swinging movement with respect thereto, said means comprising a pair of spaced, parallel card retaining rails projecting perpendicularly from the drum periphery and adapted to be received in spaced slots extending perpendicularly into cards from one edge thereof.

5. In combination, a filing drum journaled for rotation on a substantially vertical axis and having its periphery disposed on a frusto-conical surface, inclined from its lower edge upwardly and inwardly toward its axis, card retaining means on the inclined surface of the drum, and a plurality of filing cards hingedly secured at their inner edges to said means, with their inner edges inclined upwardly and inwardly, whereby the weight of the cards tends to cause them to tip laterally and to swing apart so that inspection of and posting upon the cards is facilitated.

6. In combination, a frusto-conical filing drum journaled for rotation on a substantially vertical axis and having its periphery inclined from its lower edge upwardly and inwardly toward its axis, a pair of circumferentially extending, parallel card retaining rails on said periphery, and a plurality of filing cards hingedly secured at their inner edges to said rails, with their inner edges inclined upwardly and inwardly, whereby the weight of the cards tends to cause them to tip laterally and to swing apart so that inspection of and posting upon the cards is facilitated.

RICHARD P. SCHOLFIELD.
